UNITED STATES PATENT OFFICE.

GEORGE SLOCOMBE DAVIS, OF KOGARAH, NEW SOUTH WALES, AUSTRALIA.

RAILROAD STOCK-TRUCK.

1,311,326.

Specification of Letters Patent. Patented July 29, 1919.

Application filed August 9, 1918. Serial No. 249,193.

To all whom it may concern:

Be it known that I, GEORGE SLOCOMBE DAVIS, a subject of the King of Great Britain and Ireland, residing at "Kenilworth," 5 Bellevue street, Kogarah, in the State of New South Wales, Commonwealth of Australia, have invented certain new and useful Improvements in Railroad Stock-Trucks, of which the following is a specification.

10 This invention relates to the cooling and refreshing of live stock such as cattle, horses, pigs and poultry, when in transit on railroads and confined in trucks, and is distinct from the supplying of drinking water to live 15 stock under such conditions.

The object of the invention is to provide in a railroad truck or wagon adapted for carrying such live stock, means whereby the stock may be cooled or refreshed as required 20 by a light shower of water while the truck or wagon is traveling, thus avoiding the waste of time hitherto entailed in side tracking the stock train for this purpose, and obviating the employment of trucks having removable 25 or sliding roofs.

My invention consists in the combination with a railroad truck (adapted for the carriage of stock) of means such as are herein-after described and illustrated in the accompanying drawings for achieving the before 30 stated object.

In the drawings:—

Figure 1 is a plan view of the roof of a railroad stock-truck fitted up in accordance 35 with this invention, and

Fig. 2 is a longitudinal partly sectional elevation of the top portion of the truck.

Fig. 3 is a transverse sectional elevation on line 3—3 of Fig. 1 and

40 Fig. 4 is a similar view on line 4—4 of Fig. 1; while

Fig. 5 represents at about full size a section of the drip-valve employed.

The stock truck illustrated is of the type 45 having a transversely curved roof but it will be understood that the invention is equally applicable to trucks with flat roofs.

10 represents a water-containing tank housed in a box 11 on the roof covering of the 50 truck, said tank being provided with a filling aperture 12 projecting through the top of the housing and closable by a removable cover 13 which is preferably of sufficiently loose fit to permit the passage of air. The 55 tank is fitted internally with baffles 14.14 to

minimize surging of the water, and is supported upon bearers 15.15.

To the bottom of the tank at each end are connected outlet pipes 16.16 to which are connected plug cocks 17.17 each provided 60 with an operating lever 18, said cocks and levers being so arranged that the arc of movement of the latter is in a plane at right angles to the sides of the truck.

To maintain each cock in the closed position its operating lever 18 is counterbalanced by a weight 19 and as a further safeguard a coil spring 20 exerts a pull on the lever in the same direction as said weight.

Said cocks are each connected to a separate 70 reticulation pipe system extending over the roof of the stock compartment and conforming to the sectional configuration of the roof; and each reticulation system comprises a longitudinal pipe 21, a transverse 75 pipe 22, a return longitudinal pipe 23, a transverse pipe 24, and a further return pipe 25.

At close intervals in the pipes 21 and 23 of each reticulation system are T pieces 80 26, 26, the branches of which are directed downwardly and pass through apertures in the roof of the truck; and at each end of pipes 23 and the end of pipes 25 are cross-fittings 27 of which one branch is directed 85 downwardly through the roof of the truck and the other upwardly; and into the latter are screwed vertical vent pipes 28 open at the top and through which air may escape thus preventing the formation of air-locks in the 90 pipes. The connection between the longitudinal and transverse pipes is made by cross fittings 29, into the unconnected branches of which are screwed plugs.

Into each downwardly directed branch of 95 the fittings in the reticulation pipes is screwed a drip valve 30 of particular construction and comprising (see Fig. 5) a body 31 screw threaded externally at one end and cored or bored to provide an axial passage 32 and a chamber 33, the junction of said passage and chamber constituting a valve seat 34. The chamber 33 is screw-threaded and a plug 35 screws therein, said plug having an extension 36 terminally constituting a valve 37, and a hexagon head 38 whereby the plug may be turned in the body 100 and the required adjustment of the valve effected, the plug being locked in the adjusted position by a jam-nut 39. 110

Water from the tank 10 is admitted to the reticulation pipes as and when required by opening the cocks 17, and for the manipulation of the latter, flexible wire cords 41 are attached to the levers 18, passed over the edge of the roof of the truck and through an eye 42. The cords are terminally fitted with a ring 43 which is looped over a hook 44 to maintain the cocks in the open position. Water passing the valve 37 escapes from the chamber 33 by lateral orifices 40 and drips with such frequency as is desired from the outside of the drip-valve on to the occupants of the compartment, thus providing them with sufficient moisture to minimize the risk of severe exhaustion through heat, and enabling them to complete a lengthy journey without great distress.

What I claim and desire to secure by Letters Patent is:—

1. A railroad stock car having a tank on the roof thereof, a reticulation pipe system above the roof thereof, air-vent stand-pipes connected to said system, a connection between said tank and pipe system, a cock in said connection means for operating said cock from the side of the stock compartment,

and at short intervals in said reticulation pipe system downwardly directed branches extending through the roof of the truck, and provided with pendant drip-valves.

2. A railroad stock car having a water tank on the roof thereof, plug-cocks connected to the bottom of the tank at each end, counterbalanced levers attached to the plugs of said cocks, springs to normally close the cocks, flexible cords attached to said levers, said cords leading over the edge of the roof of the car and being terminally provided with rings which engage hooks to retain the cocks in the open position, a system of reticulation pipes connected to each of said cocks and extending over the roof of the car, air vents in said pipe systems, each of the latter comprising longitudinal and transverse pipes junctioning with each other, and at short intervals in said reticulation pipes downwardly directed branches passing through the roof of the truck, and each provided with a drip valve.

Signed at Sydney New South Wales this 28th day of May, 1918.

GEORGE SLOCOMBE DAVIS.
